SAFE

Charles K. Ernst, Buffalo, N. Y.

Application January 3, 1936, Serial No. 57,380

16 Claims. (Cl. 109—1)

This invention relates to improvements in safes in which valuables may be protected from fire and theft and into which valuables may be placed while the same is locked.

In the safes shown in my Patents Nos. 1,954,667 and 1,954,668, chutes or passages of small dimensions are provided through which valuables may be deposited in the interior of the safe, while the same is locked.

The main object of this invention is to provide a safe with chutes or passages through which valuables can be readily deposited in the safe while the same is locked, but which are constructed to prevent removal of valuables therethrough from the safe.

Another object of this invention is to provide a safe having chutes, tubes or passages for valuables with means whereby such chutes or passages can be securely locked to preclude any possibility of withdrawing valuables from the interior of the safe through such chutes or passages. Another object is to provide chutes or passages of this kind of improved construction whereby withdrawal of valuables through such passages is rendered extremely difficult, if not impossible, even if the chutes or passages are not locked. Another object is to provide passages of this kind for valuables which can be unlocked only if the safe itself is unlocked, and which passages can be closed or locked without necessitating unlocking of the safe. Another object is to provide a chute or passage of this kind in which the outer or receiving end of the chute is inaccessible and into which valuables can only be placed by an intermediate part or member. Still another object of the invention is to provide chutes or passages with movable receptacles for valuables, which move into a position to receive valuables and into other positions for dropping the valuables into the chutes.

Other objects of the invention will appear from the following description and claims.

In the accompanying drawings:

Fig. 1 is a central sectional elevation of a safe embodying this invention.

Fig. 2 is a fragmentary section thereof on line 2—2, Fig. 1.

Fig. 3 is a sectional elevation taken approximately on line 3—3, Fig. 2.

Fig. 4 is a fragmentary sectional elevation on line 4—4, Fig. 1.

Fig. 5 is a fragmentary sectional elevation on line 5—5, Fig. 1.

Fig. 6 is a fragmentary sectional plan view on line 6—6, Fig. 1.

Fig. 7 is a fragmentary horizontal section on line 7—7, Fig. 5.

Fig. 8 is a fragmentary section on line 8—8, Fig. 5.

Fig. 9 is a fragmentary sectional elevation of 5 the removable locking column of the safe.

Fig. 10 is a sectional plan view of the interior of the safe shown in Fig. 1.

Fig. 11 is a fragmentary sectional elevation of a safe of modified construction.

Fig. 12 is a fragmentary section thereof on line 12—12, Fig. 11.

Fig. 13 is a section taken on line 13—13, Fig. 12.

Fig. 14 is a fragmentary transverse section on line 14—14, Fig. 12.

Fig. 15 is a fragmentary horizontal section showing the upper end of a drop tube or passage and a depositing member movable into and out of registration therewith.

Fig. 16 is an elevation showing a drop tube or 20 passage of modified construction.

Fig. 17 is a central sectional elevation of the upper portion thereof.

Fig. 18 is a section on line 18—18, Fig. 17.

Referring first to the safe shown in Figs. 1 to 9 inclusive, this safe is of a portable type enclosed in an outer shell 20, but it will be understood that the safe may be built into a basement floor, or into a part of the building as indicated in my earlier patents above referred to, in which case 30 the outer shell 20 may be omitted. Within this shell is arranged concrete or other suitable hard plastic material 21 in which suitable reinforcing metal bars or members 22 are embedded and so positioned as to resist efforts of thieves to break 35 into the interior of the safe. 23 represents a layer of sulphur or other material capable of giving off fumes if an attempt is made to cut through the safe with flames or heat. Within the interior of the mass of concrete is embodied a lining 40 or container 24 for the valuables, which may have suitable bars 25 and 26 of suitable steel or other hard material arranged about the exterior thereof and embedded in the concrete. Within the lining 24 is arranged a rotatable frame or drum 28 45 pivoted at its lower end by means of a central bearing 29 and having a pivot member 30 extending upwardly into an outer compartment or space 31 of the safe, the upper end of the pivot member being provided with a suitable handle or other means 32 for rotating the frame 28. The rotatable frame 28 supports a plurality of containers A, B, C, and D, which may be arranged in suitable compartments in the rotary member which may, for example, be substantially rectangular in 55

cross sectional shape. A fourth compartment of the rotary frame member 28 is formed to receive the locking column E of the safe, the construction of which may be of any suitable or desired kind, for example, such as described in my before mentioned patents and the column extends through a passage 34 of the safe through which access may be had to the valuables space within the lining 24. The column may be provided at the upper end thereof with a dial 35 or other suitable means for actuating a lock 36 which is preferably arranged near the lower part of the column and which may actuate a slideable bolt 37 and through a cam plate 38 connected to this bolt, the bolt may be used to actuate one or more other locking bolts 39. The bolts may engage in the walls of the rotary frame or drum 28 for the valuables compartments, or if desired, in a fixed part of the safe. The upper end of the column E terminates within the outer compartment 31 of the safe, the outer end of which compartment is closed by means of a slide 40 which may be locked by means of a suitable locking means 41 which may in turn be actuated by means of a key inserted from the exterior of the safe. Consequently, in order to obtain access to the locking column E, it is first necessary to unlock the slide 40 and move the same into a position to permit access to the outer compartment 31 of the safe, whereupon the lock for the column E may be released through the medium of a suitable lock actuating means, such, for example, as the combination lock 35 as shown. When unlocked, the column E may be lifted out of the safe, for example, by means of a bail 42 shown in Fig. 6. The central valuables container B may then be removed from the safe by reaching into the passage 34 and first moving the container B into alignment with the passage 34, whereupon this container may be pulled upwardly through the passage 34 out of the safe. The other containers A, C and D may be removed from the safe by swinging the drum 28 into positions in which these containers are in registration with the passage 34. If desired, the pivoted supporting frame or drum 28 for the valuables may also be provided in the remaining spaces with suitable containers F of such shape as to fit into the spaces left on the supporting frame or drum 28. The safe thus far described is merely illustrative of one type of safe in connection with which my improvements may be used, but it is not intended to limit this invention to the particular type of safe illustrated.

In safes of this kind it is frequently very desirable to be able to deposit valuables, such as money, papers, securities, and the like in the safe without removing the locking column E. For example, in stores or places of business, it may be desirable to keep the column E locked, except when cash receipts or certain valuables are being removed, and yet provide for deposit of valuables in the safe until the close of business, while the valuables space is locked. For this purpose, the safe shown in Figs. 1 to 7 is provided with two different types of passages or chutes through which valuables may be deposited in the safe, while the locking column E is in its locking position and both of these chutes terminate at their upper or outer ends in parts which are accessible when the valuables space is locked, for example, in the outer compartment 31 of the safe. One of these chutes is of elongated rectangular cross

section and adapted to receive bonds, stock certificates and similar papers which may be deposited in the valuables space, for example, in the container A. This chute 50 terminates at its upper end in a side wall of the outer compartment 31 of the safe and extends downwardly at an inclination to a corresponding opening 51 in the top plate 52 of the inner lining of the valuables space of the safe and in order to receive such valuables, the container A is provided with a corresponding slot 53 in alignment with the chute or passage 50. In order to prevent removal of any of the valuables deposited in the container A through the passage or chute 50 by means of wires or other implements, means are preferably provided for closing the chute 50 independently of the locking column E and for opening the chute only when the valuables space is unlocked or when the locking column is removed. In the construction shown for this purpose, a slide 55 is provided near the lower end of the chute or passage 50 and is so arranged in a suitable sheath or housing 56 embedded in the concrete or other material of the safe as to be releasably held in an open position as shown in Figs. 2, 3 and 5. In the construction shown for this purpose, see particularly Fig. 2, the slide 55 is provided with an extension or rod 57 suitably secured thereto and slideable in the direction of its length in a casing 58, the rod 57 being urged by means of a spring 59 into a position to close the passage 50. The rod, however, may be releasably held in a withdrawn position in which the slide 55 opens the passage 50 and in which the spring 59 is compressed by any suitable means which are preferably releasable so as to be actuated from a position exterior of the valuables space, for example, from the outer compartment 31 of the safe. For this purpose in the construction shown, the rod 57 is provided with a notch or recess 60, into which a detent may enter for releasably holding the rod 57 in a position in which the slide 55 is in open position. In the particular construction shown, a detent rod or member 61 is provided which is preferably arranged in a suitable guide tube or sheath 62 and yieldingly pressed into its operative or retaining position with relation to the rod 57 by means of a spring 63. The upper end of the retaining rod 61 extends into the outer compartment 31 of the safe and is provided with a knob or handle 64. Consequently, when the slide is held in open position by means of the retaining rod 61, the slide can quickly be closed by raising the retaining rod 64 out of engagement with the recess 60, whereupon the spring 59 moves the rod 57 into position to close the passage 50. Obviously, the slide 55 cannot be withdrawn into a position to open the passage 50 by any manipulation of the retaining rod 61.

It may be desirable to have the passage 50 opened only by some one authorized to have access to the valuables space in the safe, and consequently, in this construction, in order to withdraw the slide 55 to open the passage 50, it is necessary to first remove the locking column E. The bolt 57 is arranged adjacent to the passage 34 for the locking column and a projection or knob 66 is provided on the bolt 57 which is arranged in the marginal portion of the passage 34, so that the knob 66 can be reached by passing the hand into the passage 34. Consequently, the bolt 57 can be withdrawn by means of the knob 66 and the retaining bolt or rod 61 is then moved by the spring 63 into the notch 60. The passage 50, consequently, may be held in open position

after the locking column E is again locked in its passage 34, so that valuables may be dropped into the safe through the passage 50 even if the safe is locked. At the close of business, the retaining rod 61 may be raised to release the rod 57 to close the passage 50. Consequently, if burglars should succeed in removing the outer slide 40 of the safe and obtain access to the outer compartment or space 31, valuables could not be fished 10 out of the compartment A of the safe through the passage 50, if the slide 55 is across this passage, and furthermore, the passage could not be opened except by unlocking the inner valuables space.

The safe may also be provided with another 15 chute or passage into the interior thereof through which the small articles such as rolls of bills, coins, jewels or the like, can be deposited in the safe while the same is locked. In the construction shown for this purpose in Figs. 1 to 9 inclusive, a short tubular passage or chute 70 is provided, the lower end of which terminates above an opening 71 in the valuables container B. The upper end of this passage or chute 70 is arranged 20 in a space or enclosure 72 adjoining the outer 25 space or compartment 31 of the safe and enclosed, for example, by means of plates of steel or other hard material. An upper plate 73 of this enclosure is provided with an opening 74 of approximately the same size and proportions as the interior 30 of the passage or tube 70 but out of alignment therewith.

A movable member of any suitable or desired 35 form is provided within the enclosure 72 for moving valuables, placed into the enclosure through the aperture 74, into the passage 70. In the particular construction illustrated, an apertured carrier member in the form of a hollow cylinder 75 is provided in the enclosure 72 and is open at its upper and lower ends and approximately of the 40 same inner transverse dimensions as the passage 70 and the opening 74 in the plate 73. This carrier is movable from a receiving position underneath the opening 74, as shown in full lines in Fig. 5, to a position indicated in dotted lines in 45 Fig. 5, in which the carrier 75 is in registration with the passage or tube 70, so that any valuables which have been deposited in the carrier 75 through the opening 74 may be dropped through the passage 70 into the container B in the interior 50 of the safe. This carrier 75 fits fairly snugly between the walls of the enclosure 72, as shown in Fig. 7, and will, consequently, make it impossible for any fishing implement or wire to be passed through the opening 74 and passage 70 to 55 remove valuables from the interior of the safe.

The carrier 75 may be moved from its receiving position to its discharge position in any suitable or desired manner. In the construction shown, the carrier 75 is secured to an arm 77 extending 60 through a hole 78 in an upright wall 79 of the enclosure 72 and this rod 77 is rigidly connected by means of an inclined arm or bracket 80 to a 65 slideable rod 81 extending into the outer compartment 31 of the safe and having a knob or handle 82 arranged thereon. A spring 83 may be employed to normally hold the carrier 75 in receiving position. By moving the knob 82 to the right in Fig. 5, the pocket 75 will be moved into the dotted line position shown in Fig. 5, to deposit 70 valuables in the interior of the safe. The arm or bracket may be arranged in a sheath 84, Figs. 1, 6 and 7, embedded in the concrete wall of the safe. Any other means for shifting the carrier from its receiving to its discharge position may 75 be employed.

In order to make absolutely certain that no valuables are withdrawn through the passage or tube 70, a closing or locking device for this passage may be provided which may operate on a principle similar to that already described in 5 connection with the passage 50. In the construction shown, a closing device is provided in the form of a slide 85, Fig. 5, movable in a guide recess 86 of the floor or lower wall of the enclosure 72. The slide has an arm 87 extending through 10 a slot or opening 88 in a side wall of the enclosure 72 and the end of this arm 87 is secured to a slideable rod 90 arranged to slide in a guide sheath 91 and urged to move to the right in Fig. 7 by means of a spring 92. The spring in Fig. 8 is 15 shown in compressed position and when released, will move the slide 85 into a position to cover the upper end of the tube or passage 70.

The slide rod 90 is preferably held in a position in which the slide is open so that it can be 20 released to move into closing position after the inner valuables space of the safe is locked. For this purpose, the rod 90 is provided with a notch or recess 93, see Fig. 4, into which an upright holding or detent member or rod 94 may extend. 25 This detent rod is guided for vertical movement in a sheath 95, and the upper end of the detent rod is provided with a lateral extension or handle 96 extending through an aperture or slot 97 in a side wall of the outer compartment 31 of the safe. 30 A spring 98 normally urges the detent rod 94 downwardly. When the handle or extension 96 is raised against the action of the spring 98, the detent rod 94 moves out of the recess 93 and permits the slide rod 90 and slide 85 to move into 35 a closing position in which the tube or passage 70 is covered.

In order to move the slide rod 90 into a position to open the passage 70, the slide rod may be provided with a pin or extension 100 secured 40 thereto and extending through a slot 101 which opens into the passage 34 occupied by the locking column E. Consequently, when the locking column is removed from the safe, the pin or projection 100 may be moved to the right in Fig. 45 8 until the retaining member 94 engages in the slot or recess 93. The locking column E may then be again placed into its operative position and locked in place to prevent access to the valuables space. Valuables may, consequently, be deposited into the container B through the 50 passage 70 and movable carrier member 75, and when it is finally desired to completely lock the safe, as for example at the close of a day's business, the handle 96 is raised to permit the 55 slide 85 to close the passage 70, and the slide 40 85 for the outer compartment may then also be locked in its closing position. Other means for locking the passage or chute 70 may, of course, be used if desired. 60

In Figs. 11 to 15 is shown a smaller safe of the type shown in my Patent No. 1,954,667, having a valuables space or container H immediately beneath the locking column E' and either attached to the column E' or detached therefrom. 65 This safe has also an outer space or compartment 105 closed by means of a slide 106 and a tortuous drop tube or passage 107 may be provided which extends from the valuables space to a point exterior thereof, for example, to the outer compartment 70 105. This drop tube or passage is also provided with means to prevent fishing out valuables from the valuables space or container through this tube or passage while the valuables space is locked and for this purpose a separate 75

enclosure 108 is preferably provided within the outer compartment 105 and in which the outer end of the drop tube 107 terminates. The top wall of this compartment may have an aperture 109 therein out of alignment with the drop tube 107 so that valuables to be deposited in the valuables space are first placed into a movable carrier 110 through the aperture 109, which carrier is then moved into alignment with the upper end 10 of the drop tube or passage 107. This movable carrier 110 may be actuated in a manner similar to the corresponding carrier 75 hereinbefore described. In the construction shown, the carrier 110 has an arm 112 secured thereto, which arm is connected by means of a yoke or cross member 113 with a rod 114 extending into the outer compartment 105 of the safe and provided with a handle or pin 115 to facilitate moving of the carrier 110 from the position shown in Figs. 14 and 15 to the position over the drop tube or passage 107, as shown in Fig. 11. A spring 116 normally urges the carrier 110 into a position underneath the aperture 109. The yoke or cross member 113 is preferably arranged to move in a suitable recess 117 formed in the hard material or concrete 118 of the safe wall.

Means for closing the passage or tube 107 are preferably also provided, and in the construction shown, the closing means is in the form of a plate or slide 120 which when in closed position extends across the lower end of the tube or passage 107. The slide shown is guided for vertical movement in a slot or recess 121 and is provided with an upwardly extending arm 122 arranged adjacent to the passage 123 occupied by the locking column E'. A slot 124 is provided in the wall of this passage into which a pin 125 extends, one end of which is secured to the rod 122, so that the rod 122 and the slide 120 connected therewith may be moved upwardly into open position when the locking column is removed from its passage 123.

The rod 122 may be held in its upper or open position by means of a detent member or pin 127 slidably arranged in a guide tube or sheath 128 secured in fixed relation to a guide tube or sheath 129 for the rod 122. The detent member or pin 127 may engage a notch or recess 130 in the slide rod 122 and is urged by means of a spring 131 into this engaging position. A pin or knob 132, secured to the detent pin 127 and extending through a slot 133 in the outer compartment 105 of the safe, serves to permit the pin 127 to be moved out of its holding position by moving the pin or knob 132 to the left in Fig. 13. Consequently, the slide 120 is released to drop by gravity into position to lock the tube or passage 107 in a similar manner as described in connection with the slides 55 and 85. If desired, a spring may, of course, be placed into the upper end of the sheath 129 to press the slide rod into closing position.

In order to prevent the fishing out of valuables from a valuables compartment, in case the passage or tube leading to such compartment should have been left open or broken open to obtain access thereto, means are preferably provided which will act to strip from the end of a fishing line or wire passed into the valuables compartment any articles which may adhere thereto. For this purpose, I preferably provide a series of prongs or projections extending in the direction of movement of the valuables into the valuables space and having points at their ends which will tend to pierce into the valuables sufficiently

to permit them to become detached from any fishing implement which may be used. In the particular construction illustrated, I provide such prongs or projections on the container H for the valuables. The prongs preferably surround the opening 135 therein through which the valuables pass from the tube or passage 107. As shown in Fig. 12, the valuables container H is provided about the hole or aperture 135 therein with a series of integral inwardly bent pointed projections or prongs 136. Similar prongs 137 may be provided in the container B shown in Figs. 1 to 10 about the opening 76 therein and other similar prongs 138 may be provided in the container A about the opening 53 therein. It will further be understood that stripping means of any other suitable form or construction may be employed.

In Figs. 16 to 18 are illustrated drop tubes which may be used in connection with either of the safes illustrated where it is desired to deposit materials in a safe from a floor above the safe or from a considerable distance above the safe. In this case a drop tube 140 or other passage may be provided, the lower end of which extends through a top wall of a safe 141 and terminates in the valuables compartment thereof, and the upper end of this tube may be arranged in any suitable location. The upper end preferably terminates in a suitable enclosure or casing 143 of the tube 140 which houses a movable carrier, somewhat similar to the carriers 75 and 110 hereinbefore described. In the particular embodiment of the invention which is shown in the drawings, a carrier 144 is provided, which is mounted by means of arms 145 on a pivot member or post 146, the upper end of which extends through the top wall 149 of the enclosure 143 and is provided with a knob 147 for turning the post 146 to move the carrier from a receiving position shown in Fig. 17, in which this carrier registers with an aperture 148 in the top wall 149, to a position above the drop tube or passage 140. A stop 150 may be provided to correctly locate the latter position of the carrier. A substantially radial wall 151 may be provided within an enclosure or housing 143 which serves as a stop to limit the movement of the carrier 144 when in its receiving position, and which also prevents the passing of a fishing implement from the aperture 148 to the tube or passage 140, the carrier itself preventing the passing of the fishing wire or cord into the drop tube 140 about that side of the pivot 146 at which the carrier 144 moves. If desired, a coil spring 152 may be provided for normally swinging the carrier into the receiving position shown in Figs. 17 and 18.

I claim as my invention:

1. A safe having a space for valuables arranged in the interior thereof, means for locking said safe to prevent access to said valuables space, a passage in said safe and terminating at its inner end in said valuables space and through which articles may be deposited in said valuables space when said safe is locked, and means for closing said passage to prevent access to said valuables space through said passage, said means being movable into open position only when said means for locking said safe are unlocked.

2. A safe having a space for valuables arranged in the interior thereof, means for locking said safe to prevent access to said valuables space, a passage in said safe and terminating at its inner end in said valuables space and through which articles may be deposited in said valuables space

when said safe is locked, and means movable independently of said locking means for closing said passage to prevent access to said valuables space through said passage, said locking means preventing reopening of said passage until said locking means are actuated to afford access to said valuables space.

3. In a safe having walls surrounding a space for valuables, means for locking said space to prevent removal of valuables therefrom, a passage through a wall of said safe and terminating at one end in said valuables space and having the other end thereof accessible for the deposit of valuables in said space while the same is locked, and means operable when said valuables space is locked to close said passage, said means being movable into open position only when said means for locking said safe are unlocked.

4. In a safe having walls surrounding a space for valuables, means for locking said space to prevent removal of valuables therefrom, a passage through a wall of said safe and terminating at one end in said valuables space and having the other end thereof accessible for the deposit of valuables in said space while the same is locked, a passage closing member arranged within said safe wall and movable across said passage to close the same, and means operable from the exterior of said valuables space for causing said member to close said passage.

5. In a safe having walls surrounding a space for valuables, means for locking said space to prevent removal of valuables therefrom, a passage through a wall of said safe and terminating at one end in said valuables space and having the other end thereof accessible for the deposit of valuables in said space while the same is locked, a passage closing member within said safe wall and movable across said passage to close the same and movable into an open position only from the interior of said safe, and means operable from the exterior of said safe walls to cause said member to move into closing position.

6. In a safe having walls surrounding a space for valuables, means for locking said space to prevent removal of valuables therefrom, a passage through a wall of said safe and terminating at one end in said valuables space and having the other end thereof accessible for the deposit of valuables in said space while the same is locked, a spring pressed member movable across said passage for closing the same and movable into open position when said safe locking means are open, and retaining means for holding said member in open position and extending into position to be actuated when said valuables space is locked.

7. A safe including an elongated passage terminating at its inner end in a space for valuables, a column extending into said space from the outer end thereof and adapted to be locked in said space, a tube extending from the inner portion of said space to a position adjacent to the outer end of said column, and through which articles may be dropped into said space when said column is locked in said passage, and means operable while said column is locked for closing said tube to prevent access to said space.

8. A safe having an inner space for valuables and an outer compartment, separate locking means for said space and said compartment, a passage connecting said space and said compartment and through which valuables may be deposited in said inner space when the same is locked, means for closing said passage, and means

arranged in said outer compartment for actuating said closing means.

9. A safe having an inner space for valuables and an outer compartment, separate locking means for said space and said compartment, a passage connecting said space and said compartment and through which valuables may be deposited in said inner space when the same is locked, means for closing said passage, and means arranged in said outer compartment for actuating said closing means, said closing means being movable into open position only when said inner space is unlocked.

10. A safe having an inner space for valuables, an outer compartment, an elongated passage connecting the inner space and said compartment, a locking column substantially filling said passage and adapted to be locked to said safe to prevent access to said inner space, a second passage leading from said outer compartment to said space, means located exterior to said space and accessible for locking said second passage, when said column is locked in said safe, said means being movable into an unlocking position only when said locking column is unlocked.

11. A safe having an inner space for valuables, a passage leading to said space, a column substantially filling said passage and adapted to be locked to said safe while in said passage to prevent access to said valuables space, a second passage terminating at its inner end in said valuables space and having its outer end accessible for depositing valuables in said space when said locking column is locked in said first mentioned passage, and means operable when said locking column is in its locking position in said first passage for closing said second passage, said means being arranged to be moved into open position only when said locking column is unlocked.

12. A safe having a space for valuables arranged in the interior thereof, locking means for enclosing said valuables space, a passage terminating at one end in said space and having the outer end thereof spaced from said locking means and accessible for deposit of valuables into said space when said space is locked, a fixed enclosure extending over the outer end of said passage and having an opening therein out of alignment with said passage, and a pivoted carrier in said enclosure movable about an axis from said aperture to said passage for receiving valuables through said aperture and depositing them in said passage.

13. A safe having a space for valuables arranged in the interior thereof, locking means for enclosing said valuables space, a passage terminating at one end in said space and having the outer end thereof accessible for deposit of valuables into said space when said space is locked, an enclosure extending over the outer end of said passage and having an opening therein out of alignment with said passage, a carrier in said enclosure movable from said aperture to said passage for receiving valuables through said aperture and depositing them in said passage, and means operable when said valuables space is locked for closing said passage, said means being arranged to be unlocked only when said valuables compartment is unlocked.

14. A safe having a space for valuables arranged in the interior thereof, locking means for enclosing said space, a passage terminating at its inner end in said valuables space and having the outer end thereof spaced from said locking means and accessible for deposit of valuables into

said compartment when said space is locked, a member pivoted to swing about an axis and adapted to receive valuables while in one position and movable into another position to deposit said valuables in said passage, and an enclosure for said member and the upper end of said passage and said enclosure being arranged in fixed relation to said safe and having an aperture out of alinement with said passage, 10 through which valuables may be deposited in said member, said member in any position in its movement intercepting the passage of an implement through said opening and into said passage.

15. A safe having a space for valuables arranged in the interior thereof, locking means for enclosing said valuables space, a passage terminating at one end in said space and having the outer end thereof accessible for deposit of valuables into said space when said space is locked, 20 an enclosure extending over the outer end of said

passage and having an opening therein out of alinement with said passage, a carrier in said enclosure movable from said aperture to said passage for receiving valuables through said aperture and depositing them in said passage, and means operable at will independently of said carrier for closing said passage. 5

16. A safe having a space for valuables and which may be locked, a passage leading to said space and into the outer end of which valuables 10 may be inserted for deposit in said safe while the same is locked, a part for moving valuables into the outer end of said passage, means enclosing said outer end of said passage for rendering the same inaccessible except through said part, 15 and means located between said space and said part and operable independently of said part for locking said passage to prevent entrance to said space.
